UNITED STATES PATENT OFFICE.

CHARLES S. BEEBE, OF RACINE, WISCONSIN.

ROAD-CART.

SPECIFICATION forming part of Letters Patent No. 292,277, dated January 22, 1884.

Application filed August 15, 1883. (No model.)

To all whom it may concern:

Be it known that I, CHARLES S. BEEBE, of Racine, in the county of Racine, and in the State of Wisconsin, have invented certain new and useful Improvements in Road-Carts; and I do hereby declare that the following is a full, clear, and exact description thereof.

The object of my invention is to do away with the "horse-motion" in road-carts, and my device will be fully described hereinafter.

In the drawings, Figure 1 is a side elevation of my improved road-cart. Fig. 2 is a bottom view. Fig. 3 is a detail, and Fig. 4 a modification.

A is the body, B the side bars, C the springs, and D the shafts. The front ends of the springs C are secured to the cross-bar *c* of the shafts by bolts *d*, and may be raised or lowered to level the body by the nut *d'*, while any vertical play of the bolts *d* is prevented by cap-plates *d''*, that are bolted to the upper side of the cross-bar. The rear ends of the springs rest on the axle. The front ends of the side bars are clipped to the springs C just forward of their centers, and the rear portions of the side bars are connected by rods E E', that swing from arms F F', respectively, while these arms straddle the side bars and hang from their upper sides, and upon the rods E E' I rest the body A. The rod E works in bearings near the center of the body and forward of the axle, and rod E' has its bearings in the rear of the body, and the arms F F' are hung from the side bar at a greater distance apart than that between the rods E and E', this difference being such that when the body is hung the lower ends of the arms F will point to the center of the axle from in front of it, and the lower ends of the arms F' will point to the

same center from its rear. Now, therefore, as the motion of the horse has a tendency to cause the body to vibrate on an arc of the circle having a fixed center, which is in this case the axle, the arms F F', drawing from opposite sides of this center by opposing each other, have the effect of steadyng the body between them.

The arms F F' may be made either double, as shown in the drawings, or in the form of cranks, and may have their bearing either directly upon the side bars or in or on springs secured to the side bars.

To prevent jarring from the side motion of the body, rubber washers G may be interposed between arms F F' and the body.

Having thus described my invention, what I claim as new, and desire to secure by Letters Patent, is—

1. In a road-cart, side bars supported at their front ends by springs, in combination with the body suspended therefrom by arms that point toward the center of the axle from opposite sides thereof, and rods passing transversely under the body, as set forth.

2. The side bars, supported as described, in combination with the body, arms F F', depending from the side bars on opposite sides of the axle, and pointing toward the center thereof, rods E E', shafts D, and the axle, as set forth.

In testimony that I claim the foregoing I have hereunto set my hand on this 6th day of August, 1883, in the presence of two witnesses.

CHARLES S. BEEBE.
